US00D638050S

(12) **United States Design Patent**
Mage(10) **Patent No.:** **US D638,050 S**
(45) **Date of Patent:** **** May 17, 2011**(54) **SUNGLASS**(75) Inventor: **Jerome J. M. Mage**, Los Angeles, CA
(US)(73) Assignee: **Orange 21 North America Inc.**,
Carlsbad, CA (US)(**) Term: **14 Years**(21) Appl. No.: **29/357,552**(22) Filed: **Mar. 12, 2010**(51) **LOC (9) Cl.** ..... **16-06**(52) **U.S. Cl.** ..... **D16/327; D16/326**(58) **Field of Classification Search** D16/101,
D16/300-342; D29/109-110; D24/110.2;

(57) **CLAIM**

The ornamental design for a sunglass, as shown and described.

DESCRIPTION

FIG. 1 is front perspective view of the sunglass of the present invention showing my new design with the dotted lines depicting solely environmental structure and forming no part of the claimed design;

FIG. 2 is a front elevational view thereof;

FIG. 3 is a side elevational view thereof;

FIG. 4 is a rear elevational view thereof;

FIG. 5 is a top plan view thereof; and,

FIG. 6 is bottom plan view thereof.
